BRACELET OR SIMILAR ARTICLE

Saul Ritter, New York, N. Y., assignor of one-half to Marvin J. Bruner, New York, N. Y.

Application April 4, 1949, Serial No. 1,787

Term of patent 14 years

(Cl. D45—4)

To all whom it may concern:

Be it known that I, Saul Ritter, a citizen of the United States, residing at 101 Central Park West, New York city, New York, have invented a new, original, and ornamental Design for a Bracelet or Similar Article, of which the following is a specification, reference being had to the accompanying drawing, forming part thereof.

Fig. 1 is a top plan view of a bracelet embodying my new design, the end links being shown in dotted lines and the links shown in full lines, which comprise the dominant feature of the design, being repeated throughout the length of the bracelet as indicated by the links shown in broken lines;

Fig. 2 is a side elevational view of the bracelet as shown in Fig. 1; and

Fig. 3 is a bottom plan view thereof;

Fig. 4 is an enlarged top plan view of one of the top links of the bracelet;

Fig. 5 is an enlarged side elevational view of one top link taken on the line 5—5 of Fig. 4; and

Fig. 6 is an enlarged end elevational view of one top link taken on the line 6—6 of Fig. 4.

I claim:

The ornamental design for a bracelet or similar article, as shown and described.

SAUL RITTER.
